(57) **CLAIM**

The ornamental design for a motor vehicle exhaust pipe, as shown and described.

DESCRIPTION

FIG. 1 is a perspective view of a motor vehicle exhaust pipe embodying the inventive design, and fitted with exhaust tips and auxiliary pipes.

FIG. 2 is a front elevation view thereof.

FIG. 3 is a bottom plan view thereof.

FIG. 4 is a top plan view thereof.

FIG. 5 is a left-side elevation view thereof.

FIG. 6 is a right-side elevation view thereof.

FIG. 7 is a rear elevation view thereof.

FIG. 8 is a perspective view of the motor vehicle exhaust pipe of FIG. 1, shown without exhaust tips and auxiliary pipes; and,

FIG. 9 is a top plan view of the motor vehicle exhaust pipe of FIG. 8.

In FIGS. 1-7, the broken lines represent environmental elements shown for illustrative purposes only, and form no part of the claimed design.

In FIGS. 8, 9 the broken lines at the extremities of the shaded areas represent the bounds of the claimed design. The broken lines within the shaded areas represent environmental elements shown for illustrative purposes only, and form no part of the claimed design.
